US00D836966S

(12) **United States Design Patent** (10) **Patent No.:** **US D836,966 S**
(45) **Date of Patent:** **** Jan. 1, 2019**

(54) **FOOD STEAMER**

(71) Applicant: **Wong Chi Ho Kurt**, Hong Kong (CN)

(72) Inventor: **Wong Chi Ho Kurt**, Hong Kong (CN)

(73) Assignee: **CONAIR CORPORATION**, Stamford, CT (US)

(**) Term: **15 Years**

(21) Appl. No.: **29/539,757**

(22) Filed: **Sep. 17, 2015**

(51) **LOC (11) Cl.** **07-02**

(52) **U.S. Cl.**

USPC **D7/354; D7/360**

(58) **Field of Classification Search**

(57) **CLAIM**

The ornamental design for a food steamer, as shown and described.

DESCRIPTION

FIG. 1 is a perspective view of a food steamer showing a new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a right side, perspective view thereof; and,

FIG. 9 is a rear, perspective view thereof.

(Continued)

The broken lines are shown for the purpose of illustrating parts of the food steamer that form no part of the claimed invention.

1 Claim, 6 Drawing Sheets
